UNITED STATES PATENT OFFICE.

ALPHONSE E. IMBUS, OF CINCINNATI, OHIO, ASSIGNOR TO THE GLOBE REGISTER COMPANY, OF CINCINNATI, OHIO, A CORPORATION OF OHIO.

ATTACHMENT FOR MANIFOLDING TYPEWRITERS.

Application filed June 27, 1923. Serial No. 648,006.

To all whom it may concern:

Be it known that I, ALPHONSE E. IMBUS, a citizen of the United States, residing at Cincinnati, in the county of Hamilton and 5 State of Ohio, have invented a new and useful Attachment for Manifolding Typewriters, of which the following is a specification.

This invention is a device designed for 10 attachment to manifolding typewriters and the like and has for an object automatically to unwind the rolls of paper usually employed to furnish the necessary supply of paper to such typewriters, so that sufficient 15 slack is maintained at all times to enable the several sheets of paper to be fed easily upon rotation of the platen, as well as to permit of free movement of the typewriter carriage during the writing operation.

20 This and other objects are attained in the device now to be described and which has been illustrated in the accompanying drawing, in which:

Fig. 1 is a perspective view of a manifolding typewriter having an attachment embodying my invention attached thereto, a roll paper supply rack being shown in connection therewith.

Fig. 2 is a perspective view, upon an enlarged scale, of the device embodying my invention.

Fig. 3 is an enlarged sectional view taken on the line 3—3 of Fig. 2.

Fig. 4 is an enlarged fragmental perspective view of a portion of the typewriter frame, showing the outside thereof and the means I employ to secure a portion of my improved device to the typewriter.

Fig. 5 is a view of the same features shown in Fig. 4, but disclosing the reverse or inside of the frame and securing means.

In manifolding typewriters an extension 6 of the usual typewriter frame 7 carries a transversely extending track 8 upon which 45 a rearward extension 9 of the usual carriage of the typewriter travels. At the rear of extension 9 a transversely extending rod 11 is provided, over which the several superimposed sheets of paper 12 pass from a series 50 of supply rolls 13, which are conveniently located as shown, to the platen 14 of the carriage. Suspended from bar 11 are the two side members 15 and 16 of a swinging frame. These members are spaced apart by

rods 17 and 18 and beneath rod 18 a roller 19 is mounted between members 15 and 16. The hooked ends 20 and 21 are held against removal from the rod 11 by screws 22 passing through the members beneath the rod. Thus the frame is free to be swung forwardly and backwardly. Attached to frame 6 I have provided a looped track 23 which extends rearwardly and is secured to the typewriter frame at its ends 24 and 25 by clamps 26 and 27 which are attached to the frame by thumb screws 28, the ends being secured in the clamps by set screws 29. A frame swinging link or push rod 30 is connected pivotally to rod 17 by a yoke 31 to which it is riveted as shown in Figs. 2 and 3, and is prevented from sliding along the rod by a screw 32 entering a slot 33 therein. This link is attached detachably to the track 23 by means of a grooved roller 34 and a pin 35, the roller being mounted on the end of link 30, the pin being mounted on a spring 36 extending from link 30. The pin and roller are arranged to engage opposite sides of the track as shown in Fig. 2 and attachment and detachment is effected by lifting upon the spring to bring the pin away from the track 23.

In the operation of the device the sheets of paper from the rolls 13, located in a convenient position, preferably to the rear of and beneath the typewriter, are drawn over the roller 19 to the rear of the swinging frame and laid in superimposed relation to each other upon the carriage and its extension, and brought over the platen in the usual manner. The connection of link 30 with track 23 having been accomplished, the device will now function in the following manner.

Each time the carriage traverses its track, it carries with it the swinging frame, which in turn carries the link 30 held at right angles thereto. This causes roller 34, by reason of its connection with track 23, to follow the track and move the frame forwardly and backwardly. At each end of the carriage movement the frame moves forwardly and between these limits of carriage movement the roller forces the frame backwardly as it travels over the peak 37 of track 23. The effect of this movement of the swinging frame is to pull upon the paper coming from the rolls and to cause them

thus to unwind sufficiently to produce enough slack so that the line spacing may be accomplished readily without effort or slippage each time the platen is rotated at 5 either end of travel of the carriage.

Having thus described my invention what I claim is:

1. An attachment for manifolding typewriters comprising a swinging frame pivotally attached to the rear of the carriage and located beneath the paper passing over the carriage and in engagement therewith, a track rigidly attached to the typewriter frame adjacent to the swinging frame, and 10 means operatively connecting the track and swinging frame, adapted when the carriage is reciprocated to move the swinging frame, whereby the paper in engagement therewith will be caused to become slack upon completion of the swinging movement of the frame.
2. An attachment for manifolding typewriters, comprising in combination with a manifolding typewriter and a roll paper supply rack, a swinging frame pivotally attached to the rear of the carriage and located beneath the paper passing over the carriage from the rack and in engagement therewith, a track rigidly attached to the typewriter frame adjacent to the swinging frame, and 15 means operatively connecting the track and swinging frame, adapted when the carriage is reciprocated to move the swinging frame, whereby the paper in engagement therewith will be caused to be unrolled from 20

the rack and to become slack upon completion of the swinging movement of the frame. 35

3. An attachment for manifolding typewriters comprising a track adapted to be attached rigidly to a typewriter frame, a swinging frame adapted to be attached pivotally to a typewriter carriage, and a link connected with the frame and operating over the track, adapted to move the frame when the carriage is moved, said track having a shape adapted to produce greatest frame 40 movement between the limits of movement of the carriage. 45

4. An attachment for manifolding typewriters comprising in combination with a typewriter and a paper supply rack therefor, a swinging frame pivotally attached to a paper moving element of the typewriter and depending therefrom, a roller at the lower end of the swinging frame adapted to engage the paper passing from the rack 50 of the typewriter, a substantially V-shaped track rigidly attached to the typewriter frame adjacent to the swinging frame, and a roller carrying push rod rigidly attached to the swinging frame and extending therefrom into contact with the track, adapted 55 to swing the frame when transverse movement of the carriage causes movement of the push rod roller over the track, whereby the roller over the peak of the track between the limits of movement of the carriage. 60 65

ALPHONSE E. IMBUS.
